UNITED STATES PATENT OFFICE

2,144,330

MANUFACTURE OF FOOTWEAR

Daniel W. Farrington, Lynn, Mass., assignor to
 Compo Shoe Machinery Corporation, New York,
 N. Y., a corporation of Delaware

Application September 18, 1935, Serial No. 41,020

10 Claims. (Cl. 12—142)

This invention relates to the manufacture of footwear, and particularly to the making of shoes having an insole that is centrally perforate at its forepart and an outsole having a raised landed portion that complements the apertured insole in the completed shoe.

An object of the invention is to provide a method for constructing shoes having the general characteristics described above on flat bottom lasts, while avoiding certain difficulties that previously have been encountered when this has been attempted.

Complementary insoles and outsoles of the kind herein contemplated and preferred are disclosed in the Sbicca Patent No. 1,902,725. Stated more specifically, objects of the present invention are to make possible the manufacture of shoes having substantially the advantages provided by the Sbicca form of construction in factories now equipped with flat bottom lasts, without necessitating the replacement of such lasts by those having a round or convex bottom structure, or other treatment to afford room for the lasting allowance.

The problem of manufacturing single sole shoes of the Sbicca type on flat bottom lasts has been considered in the copending application of Frank Maiellano, Serial No. 36,056, filed August 14, 1935 in which various ways of meeting this problem are disclosed and claimed. The present invention has for a particular object the provision of a method whereby such type of shoe can be manufactured on flat bottom lasts without incorporating in the finished shoe a filler piece or like extra element, as is done in accordance with certain among the methods proposed in the mentioned Maiellano application.

A further object of the invention is to provide a method of manufacturing single sole shoes having perforate insoles wherein means is provided for supporting the insole on a flat bottom last in proper position to mate with a landed outsole during the sole affixing operation, and wherein such supporting means includes an element which preferably acts as a stiffener or reinforcement for the insole during lasting, and/or also comprises a shield which is capable of protecting the insole against undesired tearing and abrading adjacent its aperture during roughing operations.

Yet another object of the invention is to provide an apertured insole having associated stiffening, supporting, and/or shielding means, which is particularly useful in following the steps of the presently disclosed process.

Other objects of the invention will in part be obvious and will in part appear hereinafter.

The invention accordingly comprises the several steps and the relation of one or more of such steps with respect to each of the others, and the article possessing the features, properties, and the relation of elements, which are exemplified in the following detailed disclosure, and the scope of the invention will be indicated in the claims.

For a fuller understanding of the nature and objects of the invention, reference should be had to the following detailed description taken in connection with the accompanying drawing, in which:

Fig. 1 is a perspective view of a complementary insole and outsole blank showing the insole partially split or removed therefrom;

Fig. 2 is a perspective view of an insole and associated parts constructed and provided in accordance with the principles of the present invention;

Fig. 3 is a fragmentary transverse sectional view, on an enlarged scale, showing the insole of Fig. 2 located on a flat bottom last;

Fig. 4 is a fragmentary transverse vertical sectional view, corresponding to Fig. 3 and showing an upper lasted to the insole;

Fig. 5 is a fragmentary transverse vertical sectional view corresponding to Figs. 3 and 4 and showing the application of an outsole to the lasted upper; and

Fig. 6 is a transverse vertical sectional view across the forepart of a completed shoe constructed in accordance with the principles of the present invention.

Shoes embodying insoles and outsoles made in accordance with the teachings of the above mentioned Sbicca patent, wherein an insole is separated or split from a piece of outsole stock while leaving a raised landed portion at the central forepart area of the outsole and forming a complementary aperture in the corresponding portion of the insole, have become increasingly popular, and there are now many manufacturers who wish to make them. For reasons that are familiar to the art, and are more fully described in the above mentioned Maiellano application, this type of shoe is more readily adapted to be made on round bottom lasts than on those having flat bottoms, in view of the fact that the introduction of lasting allowance material between the complementary insole and outsole tends relatively to elevate the marginal portions of the latter with respect to its central forepart portion during the sole affixing operation, so that when flat bottom

lasts are used, it is preferable to provide means to support this portion of the outsole to assist in preventing an undesired depression or recess at this part of the shoe. However, many manufacturers have flat bottom lasts in stock, and while they prefer to make shoes having the Sbicca type construction, they naturally wish to avoid, if possible, discarding their existing flat bottom equipment and may wish to avoid additional skiving, 10 coping, or roughing operations on the leather to afford room for the upper lasting allowance. The present invention provides a shoe construction which renders this possible.

Referring more particularly to the drawing, 15 there is shown in Fig. 1 a rounded blank 10 of outsole leather which is adapted to have an insole 11 split or removed from the flesh side thereof. The removal of such insole leaves an outsole 12, and the removal is so effected that 20 a raised land 13 is left at the central forepart portion of the outsole and a corresponding aperture 14 is provided in the insole which is shaped and contoured so as exactly to fit and complement the land on the outsole. Such complementary insole and outsole may be made by the 25 three cut process described in the Sbicca Patent No. 1,902,725 or it may be performed in a single operation on the splitting machine in the manner disclosed in the copending application of 30 William C. Card, Jr., Serial No. 748,979, October 19, 1934 or in any other suitable manner capable of giving the required mated insole and outsole construction.

The outer marginal edge 15 of the insole is 35 trimmed or rounded in any suitable manner to a size somewhat less than that of the outsole. This trimming may be effected by the preliminary removal of a marginal rand before the insole is split from the outsole, as shown in Sbicca Patent No. 1,838,708; or by a separate rounding application following its removal; or in any other suitable manner.

The trimmed and apertured insole is next furnished with a ply of sheet material 16, which 40 is shaped so as to overlie the margin of aperture 14 for a short distance, its outer edges being preferably located at or slightly inwardly from the inner boundary of the marginal lasting allowance area provided at the forepart of the insole. That is, the sheet 16 is preferably dimensioned so as to lie within the inner edges of the overturned lasting allowance of an upper lasted to the insole 11. This sheet may be formed of 45 any suitable material, fiber board being preferred because it imparts rigidity to the insole during lasting and other operations, and also because it is well suited to act as a protective shield during roughing operations, as will be hereinafter pointed out. The sheet 16 is preferably attached to the insole by means of a temporary adhesive 17, such as a suitable type of latex, which may be applied entirely over one 50 side thereof, so as to provide temporary adhesive contact between the outer margin of the sheet 16 and the inner margin of the insole adjacent aperture 14, while presenting an exposed tacky surface within such aperture. This sheet is stuck to the lasting side of the insole, which is the split or grain side when it is intended that such 55 insole side shall be reassembled in opposed relation with the split or flesh side of the outsole from which it was removed. Since the split surface of the insole is sometimes smoother than the flesh side, some manufacturers prefer to reassemble the insole split from a right outsole in

reversed position on a left outsole, so that the split surface of the insole will be exposed in the interior of the shoe. If this is done, the sheet 16 should be stuck to the flesh side, which will then be the lasting side. If desired, the stiffening sheet 16 may be attached to the insole prior to the trimming operation at 15, assuming that the latter is performed after removal of the insole from the outsole, in which case it will serve to strengthen the insole during such operation. 10

A filler piece is next applied to the central forepart portion of the insole on the opposite side thereof from sheet 16. This filler piece is preferably of composite structure, comprising a ply 18, which also preferably is formed of fiber board 15 in order to impart added stiffness and strength to the insole, to which is permanently cemented a ply 19 of felt or like material. The fiber board ply 18 may be somewhat larger than the sheet 16, and the felt ply 19, which is thicker than the 20 fiber board, is preferably feathered along its outer margin, as illustrated. The thickness of the composite filler piece equals or approximates that of the upper materials which are to be lasted to the insole. Such filler piece is located across the 25 aperture 14, the ply 18 thereof being stuck to the temporary adhesive 17 which is exposed through such aperture.

An alternative and presently preferred procedure for assembling the sheet members 16 and 30 the filler piece or member with the insole comprises coating the free face of the filler piece 35 ply 18 with temporary adhesive such as a suitable form of latex and sticking the filler piece to the inclined margin of the insole bounding the aperture 14. The protective sheet member 16 is then stuck to the tacky surface of the filler member through such aperture. This procedure has the advantage of preventing the undesired deposit of latex or other foreign material 40 on the lasting side of the insole adjacent its aperture margins, thus leaving a clean surface at such margin for the reception of permanent cement, such as pyroxylin, during the subsequent outsole affixing operation. 45

The insole thus constructed is located on a last, which may have a flat bottom, as shown in Fig. 3. In locating the insole, the felt filler piece ply is positioned against the bottom of the last, and the stiffening ply 16 is outwardly exposed. 50

The assembled upper 20 is next pulled over the last and its lasting allowance 21 is lasted thereto, preferably by means of pyroxylin cement or the like, although other types of lasting, such as stitching or stapling may be adopted, if desired. When cement side lasting is employed, the marginal lasting allowance of the insole should be roughed prior to its location on the last bottom, and the presence of the fiber board sheet 60 16 prevents the roughing tool used for such operation from tearing or abrading the thin inner edge of aperture 14. In this respect it acts as a shield or template to limit the area of operation of the roughing tool. The lasting allowance 21 65 around the forepart of the shoe is trimmed so as not to overlap the sheet 16, as is indicated at Fig. 4, and this overturned lasting allowance may also be roughed to prepare it for cement attachment to an outsole. The sheet 16 also acts as a 70 protective shield for the insole during this bottom roughing operation.

After the upper has been permanently lasted to the insole, the sheet 16 is removed by tearing or pulling it away from the bottom of the lasted 75

upper, the temporary cement readily permitting this operation. After removal of sheet 16, the filler piece is no longer positively attached to the insole, but is held in position beneath the insole aperture by frictional contact with the lasted insole and the last bottom.

The removal of ply 16 also exposes aperture 14, and the landed outsole 12 is positioned against the bottom of the lasted upper with its land 13 fitted into and exactly complementing the exposed aperture 14, as shown in Fig. 5. The marginal portion of such outsole, prior to its location against the shoe bottom, is preferably roughed and coated with a permanent cement, but it need not be skived or otherwise coped to compensate for the thickness of the lasting allowance materials at 21, even when flat bottom lasts are used, because the central apertured portion of the insole is supported in a relatively elevated position by the composite filler piece. The effect thus obtained is similar to that occurring when a round bottom last is used in that the central forepart portion of the insole is so supported and elevated that the pressure applied to the outsole during the cement sole affixing operation cannot act to depress the central forepart portion thereof as would be the case under certain conditions if the land 13 were permitted directly to abut a flat bottom last. Any suitable form of sole affixing press may be utilized to cement attach the outsole to the lasted upper.

Following the outsole affixing operation, the shoe is delasted, at which time the composite filler piece, which is no longer attached to the insole, may be freely removed, thus leaving (Fig. 6) a single sole shoe wherein the outsole land 13 is exactly mated and flush with the inner edge of insole aperture 14, and in which no extraneous filler or reinforcing piece remains. The ultimately formed shoe may thus have exactly the construction heretofore obtained by lasting on round bottom lasts, while permitting the use of flat bottom lasts in those factories where such equipment is more readily available.

45 The removed ply 16 and the filler piece may be subsequently reassembled with another insole, a fresh coating of adhesive 17 preferably being applied from time to time when this is done.

It will be seen that there has been provided a method and a construction which is well suited to fulfill its intended functions.

It will be understood that various changes may be made in the described illustrative structure and process without departing from the purview of the invention. Thus the sheet material 16 need not be of fiber board, nor need it be configured to cover the entire aperture 14, since a relatively narrow strip or band spanning such aperture will afford a sufficient anchorage for the filler piece. Of course, if such a narrow strip or band is employed, it will not provide the insole rigidifying and shielding functions afforded by a complete fiber board sheet such as that illustrated at 16. Also, the filler piece may be of unitary 65 rather than composite structure if desired, and may be removably attached to the sheet or strip 16 in any desired manner. Further, certain advantages of the invention may be obtained by discarding sheet 16 altogether, and temporarily adhesively fastening the marginal portions of the filler piece to the inward margin of the insole bounding the aperture 14. In such a construction the filler piece provides a reinforcement for the insole during lasting operations and the like, and 70 it may be pulled away from the interior of the

shoe after completion thereof so as to avoid leaving an extra filler element therein. However, the particularly described and illustrated forms are at present regarded as preferred embodiments of the invention.

5

Since certain changes in carrying out the above method, and certain modifications in the article which embody the invention may be made without departing from its scope, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim 20 as new and desire to secure by Letters Patent is:

1. A method of making shoes which comprises providing an outsole having a raised land at its central forepart portion and an insole having an apertured central forepart portion corresponding with said land, positioning a sheet member on one side of said insole across its aperture, positioning a filler member on the opposite side of said insole and adhesively fastening it to said sheet member through said aperture, locating said insole on a last with said filler member next to the last bottom, lasting an upper to said insole, removing said sheet member and affixing said outsole to the lasted upper with its land fitting said insole aperture.

35

2. A method of making shoes which comprises providing an outsole having a raised land at its central forepart portion and an insole having an apertured central forepart portion corresponding with said land, positioning a sheet member on one side of said insole across its aperture, positioning a filler member on the opposite side of said insole, temporarily attaching one of said members to said insole, and temporarily attaching the other of said members to such first named member through said aperture, locating said insole on a last with said filler member next to the last bottom, lasting an upper to said insole, removing said sheet member, and affixing said outsole to the lasted upper with its land fitting said insole aperture.

45

3. A method of making shoes which comprises providing an outsole having a raised land at its central forepart portion and an insole having an apertured central forepart portion corresponding with said land, positioning a sheet of material to one side of said insole across its aperture, positioning a filler member on the opposite side of said insole, temporarily attaching one of said members to said insole, and temporarily attaching the other of said members to such first named member through said aperture, locating said insole on a flat bottom last with said filler member facing the last bottom, lasting an upper to said insole, removing said sheet member from said insole and from said filler member to expose said insole aperture, affixing said outsole to the lasted upper with its land fitting said aperture, delasting the shoe thus formed, and removing said filler member from the interior thereof.

55

4. A method of making shoes which comprises providing an outsole having a raised land at its central forepart portion and an insole having an apertured central forepart portion corresponding 75

with said land, temporarily attaching a sheet of material to one side of said insole across its aperture, roughing the marginal portion of said insole beyond said material, positioning a filler piece on the opposite side of said insole and temporarily attaching it to said material through said aperture, locating said insole on a flat bottom last with said filler piece facing the last bottom, cement lasting an upper to the roughed 10 margin of said insole, bottom roughing such lasted upper, removing said material from said insole and from said filler piece to expose said insole aperture, cement affixing said outsole to said lasted upper with its land fitting said aperture, delasting the shoe thus formed, and removing said filler piece from the interior thereof.

5. A method of making shoes which comprises providing an outsole having a raised land at its central forepart portion and an insole having an apertured central forepart portion corresponding with said land, positioning a protective sheet member on one side of said insole across said aperture and over the adjacent insole margin bounding said aperture, positioning a filler member on the opposite side of said insole, temporarily adhesively fastening one of said members to the insole, and temporarily adhesively attaching the other of said members to said first named member through said aperture, roughing the marginal portion of said insole beyond said sheet member, locating said insole on a flat bottom last with said filler member facing the last bottom, cement lasting an upper to the roughed 10 margin of said insole, bottom roughing such lasted upper, removing said sheet member from said insole and from said filler member to expose said insole aperture, cement affixing said outsole to said lasted upper with its land fitting said aperture, delasting the shoe thus formed, and removing said filler member from the interior thereof.

6. A method of making shoes which comprises providing an outsole having a raised land at its central forepart portion and an insole having an apertured central forepart portion corresponding with said land, positioning a protective sheet member on one side of said insole across said aperture and over the adjacent insole margin bounding said aperture, positioning a filler member on the opposite side of said insole, temporarily adhesively fastening one of said members to the insole, and temporarily adhesively attaching the other of said members to said first named member through said aperture, roughing the marginal portion of said insole beyond said sheet member, locating said insole on a flat bottom last with said filler member facing the last bottom, cement lasting an upper to the roughed 10 margin of said insole and trimming the lasting allowance of such upper until it clears said sheet member, bottom roughing such lasted upper, removing said sheet member, cement affixing said outsole to said lasted upper with its land fitting said insole aperture, delasting the shoe thus formed, and removing said filler member from the interior thereof.

7. A method of making shoes which comprises providing an outsole having a raised land at its central forepart portion and an insole having an apertured central forepart portion corresponding with said land, positioning a protective sheet member on one side of said insole across said aperture and over the adjacent insole mar-

gin bounding said aperture, positioning a filler member on the opposite side of said insole, temporarily adhesively fastening one of said members to the insole, and temporarily adhesively attaching the other of said members to said first 5 named member through said aperture, roughing the marginal portion of said insole beyond said sheet member, locating said insole on a flat bottom last with said filler member facing the last bottom, cement lasting an upper to the roughed 10 marginal portion of said insole and trimming the lasting allowance of such upper until it clears said sheet member, bottom roughing such lasted upper, removing said sheet member, roughing the marginal portions of said outsole, applying cement to the roughed portions of such outsole and of the bottom of said lasted upper, affixing said outsole to said lasted upper under pressure with its land fitting said insole aperture, delasting the shoe thus formed, and removing said 15 filler member from the interior thereof.

8. A method of making shoes which comprises providing an outsole having a raised land at its central forepart portion and insole having an apertured central forepart portion corresponding with said land, coating one side of a reinforcing sheet with a temporary adhesive, sticking the marginal portions of said sheet to the margin of said insole aperture by means of said adhesive, positioning a filler piece on the opposite side of 25 said insole from said sheet and sticking it to the latter through said aperture, locating said insole on a flat bottom last with said filler piece facing the last, lasting an upper to the marginal portions of said outsole located outwardly from 30 said sheet member, bottom roughing such lasted upper, removing said sheet member, and cement affixing said outsole to said lasted upper with its land fitting said insole aperture.

9. A method of making shoes which comprises providing an outsole having a raised land at its central forepart portion and an insole having an apertured central forepart portion corresponding with said land, coating one side of a filler piece with a temporary adhesive, sticking the marginal portions of said filler piece to the 40 margin of said insole aperture by means of said adhesive, positioning a sheet member on the opposite side of said insole from said filler piece and sticking it to the latter through said aperture, locating said insole on a flat bottom last with said filler piece facing the last, lasting an upper to the marginal portions of said outsole located outwardly from 45 said sheet member, bottom roughing such lasted upper, removing said sheet member, and cement affixing said outsole to said lasted upper with its land fitting said 50 insole aperture.

10. An insole for use in the manufacture of shoes of the class described, said insole having an aperture through its central forepart portion, a fiber board sheet of greater extent than said aperture and of less extent than said insole forepart, a second fiber board sheet positioned on the opposite side of said insole, temporary adhesive 55 coating one face of one of said sheets, said coated sheet being stuck to the bounding margin of said insole aperture and being stuck to the other sheet through said aperture, and a felt pad cemented to said second sheet, said pad being positioned 60 opposite the central forepart portion of said insole.

DANIEL W. FARRINGTON.
